U.S. Cl. D80—9

Fig. 1.

In FIGURE 4 the side not shown is identical with the side shown.

The broken line representation of mops and brooms in FIGURE 1 is for purposes of illustration only.

I claim:

The ornamental design for a display stand for mops and brooms, as shown and described.
